FLUORESCENT LAMP FIXTURE

James H. Kuhns, Indianapolis, Ind.

Application January 13, 1942, Serial No. 426,565

11 Claims. (Cl. 240—78)

This invention relates to electric lighting fixtures and particularly to an assembly for fluorescent tube mounting and light control. A primary object of the invention is to provide a fixture wherein one or more fluorescent tubes may be employed for direct, diffused, or reflected lighting, all in the absence of or with a minimum use of metal in the fixture. By use of the invention, the customarily employed metallic base and reflecting shield may be dispensed with. This is a feature that is of great importance during the present shortage of metal and the high demand for good lighting to promote the maximum possible production of war goods.

A further primary object of the invention is to provide means for controlling light emitted from fluorescent tubes to the end that the direct glare may be removed from the normal line of eyesight of individuals in the vicinity of the source of light. A still further primary object of the invention is to provide a structure wherein reflectors and diffusing devices may be made out of glass by any suitable mode of production, such as by pressing, molding or forming from flat sheets. A still further important object of the invention is to provide non-metallic means for supporting the glass members of the fixture, and further to form such means in a manner employing the minimum amount of material.

While reference has above been made to the use of glass, it is within the scope of the invention to employ in the place thereof or in part plastics in the nature of the now well known synthetic resins. Other objects and advantages of the invention, including the ease of assembling and disassembling the structure, particularly for cleaning purposes, the neat and aesthetic appearance of the fixtures, and particularly the unique combinations of elements as set forth in the appended claims, will become apparent to those versed in the art in the following description of the invention as illustrated in the accompanying drawings, in which

Fig. 1 is a view in side elevation in partial section of a structure embodying the invention;

Fig. 2, a view in top plan;

Fig. 3, a view in end elevation;

Fig. 4, a view in vertical section on the line 4—4 in Fig. 1;

Fig. 5, a similar view but in modified form;

Fig. 6, also a similar view in still further modified form;

Fig. 7, a view in elevation from the inside of one of the glass enclosing members shown in the form embodied in Figs. 1-4;

Fig. 8, a view in perspective of a modified form of a glass housing section;

Fig. 9, a view in side elevation in partial section of a further modified form of the invention; and

Fig. 10, a view in end elevation thereof.

Like characters of reference indicate like parts throughout the several views in the drawings.

Referring first to that form of the invention as illustrated in Figs. 1-4, a supporting member 10, cruciform in section, is provided with spaced apart lamp holders 11 and 12 fixed in spaced apart relation in pairs on opposite sides of the depending portion of the member 10, Figs. 1 and 4, and fluorescent tubes 13 and 14 are interengaged between the respective holders. This member 10 may be made out of any suitable material, normally metal, but in the absence of available metal, may be made out of wood, fiber board, or any of the suitable well known plastics. The detail construction of these lamp holders 11 and 12 are not herein shown since these members are standard parts commercially obtainable.

From the upper face of the transversely extending wings 15 and 16 of the member 10 are fixed upwardly extending posts 15, 16 and 17, 18 respectively on each side of the upwardly extending rib of the holding member 10. The respective pairs of posts 15, 16 and 17, 18 are spaced apart a considerable distance along the holding member 10.

A glass housing is provided to be formed by two symmetrical glass members 19, Fig. 7, herein shown in the one particular form as being a curved sheet of glass having holes 20, 21 therethrough near one longitudinal margin of the glass spaced to receive the respective posts 15, 16 or 17, 18, as the case may be, therethrough to have the underside of that margin portion of the member 19 rest upon the transversely extending wing of the supporting member 10, whereby the remainder of that glass member curves outwardly, downwardly and around to terminate substantially in the central vertical plane extending through the supporting member 10.

While in this particular form of housing the two members 19 may be allowed to abut one another by their lower inwardly turned edges, preferably a molding 22 having an H-section is employed whereby the lower marginal edge portions of the two members 19 may be frictionally and elastically engaged within the channels of this molding 22, as best shown in Fig. 4. The support member 10 may be carried by any suitable means, herein shown as by chains 23, 24 attached to the

upwardly extending rib of the supporting member 10 by any suitable means, such as by the links 25, 26 respectively.

The necessary electrical equipment may be carried by the supporting member 10 either within or outside of the housing formed by the members 19, herein suggested as having the starter member 21 mounted in the usual manner on one of the lamp holders 12, Fig. 4, and the ballast coil 28 mounted outside of the housing on the upwardly extending rib portion of the supporting member 10, Figs. 1 and 2.

The ends of the housing formed by the members 19 may be left open or, if desired to be closed, glass end plates 29 formed to have a peripheral margin of the same contour as that defined by the walls of the combined members 19 may be placed at each end of the holding member 10 and there secured in any suitable manner, herein indicated as by means of screws 30 passing through the plate 29 in each instance and engaging with the supporting member 10 therebehind.

Each of these glass members 19 may, of course, be given any degree of curvature desired, or may be formed to have flat sections between bends, all depending upon the particular artistic design desired. In any event, each glass member 19 may be formed to be entirely transparent for the maximum emission of light in all directions possible from the two lamps 13 and 14. However, a better distribution of light downwardly is to be had by providing a highly reflecting surface on the upper portions (either inside or out) of these members 19, for example, over such areas as indicated by the numeral 31. This reflecting surface may consist of an applied enamel but preferably of the usual silver surface commonly employed for mirrors or highly reflecting surfaces. Where this reflecting surface 31 is provided, the balance of the glass wall of the member 19 in each instance may be formed to be entirely transparent, or may have its surface or even its entire wall so constructed as to cause a diffusing effect of the light. A surface (either inside or outside) of each member 19, for example, below the area 31 may be provided with the molded or rolled-in designs commonly employed to make the so-called "frosted" surface, or this area may be sand-blasted. In any event, regardless of how formed, this part of the wall of the member 19 is preferably made to be of a light diffusing nature.

To form the most highly efficient fixture, an additional reflector 32 is provided to have a convex surface presented toward and above the lamps 13 and 14. This reflector 32 is preferably made out of glass to be formed into the indicated shape by any of the well known methods. This reflector 32 may be mounted within the housing formed by the members 19 and above the lamps 13 and 14 in any suitable manner, preferably carried by the supporting member 10. One particular method of mounting this reflector 32 is as follows. The holding member 10 is provided with a longitudinal slot therethrough spaced between the undersides of the transversely extending wings of that member and above the level of the lamps 11 and 12. The reflector 32 is inserted through this slot by a longitudinal marginal edge and pushed around to a central position whereby, when the two glass enclosing members 19 are in closed position, Fig. 4, the longitudinal marginal edges of this reflector 32 are in substantial abutment with the inner faces of those members 19. Obviously the length of the reflector 32 is less than the length of that part of the holding mem-

ber 10 which extends below its transversely extending wings 75 and 76.

The structure so far described provides a complete fluorescent lamp fixture wherein a pair of lamps 13 and 14 are mounted within a glass housing, all without the use of any metal entering into the fixture proper, particularly in respect to the base provided for supporting the lamps and for supporting the reflectors. As above indicated, 10 the holding member 10 may be made out of metal if available. In this case it is to be seen that the amount of metal required is reduced to a very small quantity and metal or the other materials suggested may be interchanged depending upon their availability and relative costs. Obviously 15 central portions of the holding member 10 may even be cut away to reduce the weight of material employed in any case.

The unique structure above set forth permits 20 ready cleaning of the external wall of the assembly by simply wiping off the outsides of the glass members 19. To clean the inner portions, or to replace lamps 13 or 14 as the situation may 25 require, one of the glass housing sections 19 may be pulled laterally from its lower side to disengage its marginal edge from the molding 22 and then lifted upwardly to disengage it from its respective posts 15, 16 or 17, 18 depending upon which member 19 is first removed. The reflector 30 32, although simply inserted through the holding member 10, remains in position. In the same manner the other section 19 of the housing may be removed, or both sections may be removed. The particular means for mounting these sections 35 19 as above described cause the two sections to tend to swing inwardly one toward the other by their lower ends so that the two sections normally remain in fixed positions when one abuts the other through the molding 22 without having to use any other additional means.

40 In some instances, the two sections of the glass housing about the lamps 13 and 14 may be so formed as to be left open from their undersides, such as is indicated in Fig. 5. In this form, the 45 two sections 33 and 34 constituting the shielding and side reflecting surfaces are arcuate glass sections supported entirely by hanging from the transversely extending wings of the supporting member 10, and maintained thereon as before by the posts 15, 16 on the one side and 17, 18 on the other. The glass reflector 32 may be used as before and in this case, its outer longitudinal edges may further serve as supporting means against which the members 33 and 34 may swing and be supported. In the same manner the members 33 55 and 34 may be selectively formed to be transparent, translucent, an upper portion of a highly light reflecting character and the lower portion of a light diffusing character or any combination thereof. 60 This form of the invention would be used where the maximum possible radiation of light from the lamps 13 and 14 is desired, particularly in a downward direction.

Other means for supporting the sections forming the reflector and inclosing members about the lamps 13 and 14 may be employed, one other such means being indicated in Fig. 6 wherein the same style of supporting member 10 is indicated. In this instance, however, the upper 70 marginal edges of the two housing members 35 and 36 are curved upwardly to engage within slots opening downwardly and provided along each side of the upwardly extending part of the member 10. In the form shown in Fig. 6, brackets 75 37 and 38 are attached on opposite sides of

the upper part of the member 10 to form such slots between that member 10 and outwardly spaced lower edges of the brackets 37 and 38. The housing members 35 and 36 are respectively mounted on the member 10 by first engaging the upturned edges thereof within those sockets and then swinging the glass members downwardly to allow them to swing toward each other by their lower ends. Obviously the same type of mounting may be employed for the form of housing members shown in Fig. 5.

The foregoing description has been made in reference to housing members having open ends, and requiring separate end closures if desired. Referring to Fig. 8, a housing member 39 may be formed with integral closures 40 and 41 by any suitable means, such as by molding. In this case a top rib 42 may also be molded along the member 39 for engagement in that form of support as shown in Fig. 6 and holes 43, 44 may be provided along the top marginal edge portion for mounting as in the first described form. In any event, it is obvious that these lamp housing sections may be formed in any desired manner, such as by pressing them into shape, molding, or forming them from original flat sheets.

Some of the fluorescent lamps are mounted between parallel end walls and where such a type of mounting is desired or may be necessary, a structure such as indicated in Figs. 9 and 10 may be employed. In this form of the invention, a support member 45, made out of any suitable material and having an inverted T-section, is formed to the desired length and is provided with two spaced apart downwardly extending end brackets 46 and 47. Lamp holders 48 and 49 are fixed on the inner opposing faces of these respective brackets 46 and 47 to receive the lamp 50 therebetween. Then, as above described, the reflector housing members may be mounted above and around the lamps 50 to have the upper ends of those reflector members engaged by means supported by the outwardly extending flanges of the support member 45, shown in this particular instance as being posts 51 and 52 mounted thereon for the reflector engagement. The internal central convex reflector 32 may be employed in this structure as well as in the other structures above defined by supporting it by its ends on brackets 53 and 54 extending inwardly from the opposing faces of the lamp brackets 46 and 47.

In regard to the question of ventilation, that situation is taken care of amply where the ends of the housing members are left open. However, when the closed end structure is employed, the central supporting member 10, assuming in effect in general a back bone of the fixture may be cut away in central portions at least between the upper marginal edges of the members 19 to leave one or more air passageways. Referring to Figs. 1 and 2, for example, slots 55 may be formed to extend entirely through the vertically disposed part of the member 10 to extend above and below the upper marginal edges of the housing members 19. When the reflector 32 is employed, heat may escape along a current of air discharging around either or both ends of the reflector 32 within the closed end members 19, which current may flow across the upper side of the reflector and escape through the upper portions of the openings 55 which open to the atmosphere above the top sides of the members 19.

It is therefore to be seen that by the structures herein disclosed, a very simple but efficient fluorescent lamp fixture is provided that may be

made up to have a wide range of designs in respect to the shape of the reflectors and housing. While the members 19 have herein been shown as being co-extensive in length with the over-all length of the fixture in general, obviously these members 19 may be made in shorter lengths, one to abut the other, so that in case of breakage, one member section may be replaced without having to replace the entire side. The structure is very easily assembled and disassembled and most importantly, avoids the use of any extended area of metal that has heretofore been employed as a reflecting surface and as an upper housing in particular.

Therefore while the invention has been described in more or less precise detail, it is obvious that many structural changes may be employed without departing from the spirit of the invention and I therefore do not desire to be limited to that precise form beyond the limitations as may be imposed by the following claims.

I claim:

1. A lamp fixture comprising an elongated skeleton frame member having oppositely, outwardly, laterally extending wings therealong, lamp supporting means carried by said frame, a two-part, longitudinally divided lamp housing, each of said housing parts having an upper in-turned marginal portion to overlap and rest respectively on the top sides of said wings to have the major portion of each housing part extend outwardly and downwardly therefrom tending to rock over said wings one toward the other, and stop means carried by said frame to engage said housing part portions above said wings to form a limiting stop against outward travel of said portions and to limit the degree of downward rocking of the housing parts, over the edges of said wings.

2. A lamp fixture comprising an elongated skeleton frame member having oppositely, laterally extending wings therealong, lamp supporting means carried by said frame, a two-part, longitudinally divided lamp housing, each of said housing parts having an upper in-turned marginal portion to overlap and rest respectively on the top sides of said wings to have the major portion of each housing part extend outwardly and downwardly therefrom tending to rock over said wings one toward the other, stop means carried by said frame to engage said housing part portions to limit positively the degree of downward rocking of the housing parts, and removably retain said portions on said wings, and an elongated reflector carried by said frame below said wings with longitudinal edges parallel in longitudinal directions with the housing parts and spaced to abut substantially the inner opposing faces of said housing parts above the lower edges of the housing parts.

3. A lamp fixture comprising an elongated skeleton frame member having oppositely, laterally extending wings therealong, lamp supporting means carried by said frame, a two-part, longitudinally divided lamp housing, each of said housing parts having an upper in-turned marginal portion to overlap and rest respectively on the top sides of said wings to have the major portion of each housing part extend outwardly and downwardly therefrom tending to rock over said wings one toward the other, stop means carried by said frame to engage said housing part portions to limit positively the degree of downward rocking of the housing parts, and removably retain said portions on said wings, and an elongated re-

flector carried by said frame below said wings with longitudinal edges parallel in longitudinal directions with the housing parts and spaced to abut substantially the inner opposing faces of said housing parts above the lower edges of the housing parts; said reflector being mounted to be above the position of a lamp carried by the frame and having a convex under surface.

4. A lamp fixture comprising an elongated skeleton frame member having oppositely, outwardly, laterally extending wings therealong, lamp supporting means carried by said frame, a two-part, longitudinally divided lamp housing, each of said housing parts having an upper inturned marginal portion to overlap and rest respectively on the top sides of said wings to have the major portion of each housing part extend outwardly and downwardly therefrom tending to rock over said wings one toward the other, and stop means carried by said frame to engage said housing part portions above said wings to form a limiting stop against outward travel of said portions and to limit the degree of downward rocking of the housing parts, over the edges of said wings; said stop means comprising slots open from their under sides only above inner portions of said wings, and lips along said housing part marginal portions upturned to enter said slots.

5. A lamp fixture comprising an elongated skeleton frame member having oppositely, outwardly, laterally extending wings therelong, lamp supporting means carried by said frame, a two-part, longitudinally divided lamp housing, each of said housing parts having an upper inturned marginal portion to overlap and rest respectively on the top sides of said wings to have the major portion of each housing part extend outwardly and downwardly therefrom tending to rock over said wings one toward the other, and stop means carried by said frame to engage said housing part portions above said wings to form a limiting stop against outward travel of said portions and to limit the degree of downward rocking of the housing parts, over the edges of said wings, said stop means comprising posts upturned from said wings to extend through holes provided in said housing part marginal portions.

6. A lamp fixture comprising an elongated skeleton frame member having oppositely, laterally extending wings therealong, lamp supporting means carried by said frame, a two-part, longitudinally divided lamp housing, each of said housing parts having an upper inturned marginal portion to overlap and rest respectively on the top sides of said wings to have the major portion of each housing part extend outwardly and downwardly therefrom tending to rock over said wings one toward the other, stop means carried by said frame to engage said housing part portions to limit positively the degree of downward rocking of the housing parts, and removably retain said portions on said wings, and an elongated reflector carried by said frame below said wings with longitudinal edges parallel in longitudinal directions with the housing parts and spaced to abut substantially the inner opposing faces of said housing parts above the lower edges of the housing parts, said reflector being laterally shiftable between said housing parts whereby said parts may be centralized by lateral shifting of the reflector.

7. A lamp fixture comprising an elongated skeleton frame member having oppositely, laterally extending wings therealong, lamp support-

ing means carried by said frame, a two-part, longitudinally divided lamp housing, each of said housing parts having an upper inturned marginal portion to overlap and rest respectively on the top sides of said wings to have the major portion of each housing part extend outwardly and downwardly therefrom tending to rock over said wings one toward the other, and stop means carried by said frame to engage said housing part portions to limit positively the degree of downward rocking of the housing parts, and removably retain said portions on said wings, said frame member being substantially cruciform in cross-section in parts at least, whereby said wings form the cross bar of the cross and the vertical portion thereof forms mounting means above and said lamp supporting means below said wings.

8. A lamp fixture comprising an elongated skeleton frame member having oppositely, laterally extending wings therealong, lamp supporting means carried by said frame, a two-part, longitudinally divided lamp housing, each of said housing parts having an upper inturned marginal portion to overlap and rest respectively on the top sides of said wings to have the major portion of each housing part extend outwardly and downwardly therefrom tending to rock over said wings one toward the other, and stop means carried by said frame to engage said housing part portions to limit positively the degree of downward rocking of the housing parts, and removably retain said portions on said wings, said frame member being substantially cruciform in cross-section in parts at least, whereby said wings form the cross bar of the cross and the vertical portion thereof forms mounting means above and said lamp supporting means below said wings, and said frame member being provided with a ventilating slot through said vertical portion, said slot extending across and opening above and below said wings.

9. A lamp fixture comprising an elongated skeleton frame member having oppositely, laterally extending wings therealong, lamp supporting means carried by said frame, a two-part, longitudinally divided lamp housing, each of said housing parts having an upper inturned marginal portion to overlap and rest respectively on the top sides of said wings to have the major portion of each housing part extend outwardly and downwardly therefrom tending to rock over said wings one toward the other, stop means carried by said frame to engage said housing part portions to limit positively the degree of downward rocking of the housing parts, and removably retain said portions on said wings, and a lamp reflector extending longitudinally of said frame member and thereunder, said lamp supporting means serving also to carry said reflector.

10. A lamp fixture comprising an elongated skeleton frame member having oppositely, laterally extending wings therealong, lamp supporting means carried by said frame, a two-part, longitudinally divided lamp housing, each of said housing parts having an upper inturned marginal portion to overlap and rest respectively on the top sides of said wings to have the major portion of each housing part extend outwardly and downwardly therefrom tending to rock over said wings one toward the other, stop means carried by said frame to engage said housing part portions to limit positively the degree of downward rocking of the housing parts, and removably retain said portions on said wings, said

frame member having a depending portion extending centrally and longitudinally thereof, said depending portion having a transverse slot, and a reflector extending through said slot to have the reflector edges in substantial abutment with said housing parts.

11. A fluorescent light fixture comprising a rigid backbone substantially cruciform in cross-section, a housing having spaced apart upper marginal edge portions resting on the cross arm 10

of said backbone, means for mounting a fluorescent lamp on the backbone part below the cross arm, said part being transversely slotted above said mounting means, and a reflector inserted through said slot to extend laterally from each side of said part toward the walls of said housing, whereby said walls limit shifting of the reflector through said slot.

JAMES H. KUHNS.
